UNITED STATES PATENT OFFICE.

JAMES A. ROSS, OF CHICAGO, ILLINOIS.

BOILER.

Application filed May 19, 1922. Serial No. 562,115.

To all whom it may concern:

Be it known that I, JAMES A. ROSS, a citizen of the United States, and a resident of the city of Chicago, county of Cook, and State of Illinois, have invented certain new and useful Improvements in Boilers, of which the following is a specification.

My invention relates to new and useful improvements in boilers and particularly 10 improved arch constructions and has for its principal object an improved construction of this character which will be highly efficient in use, the present invention constituting an improvement over my prior application 15 filed on or about June 24, 1921 for improvements in boilers and bearing Serial No. 480,009.

A further contemplation of the invention is to construct a hollow arch support 20 communicating with the water compartments of the boiler. Within the arch support I arrange horizontal baffle-plates to assure a rapid circulation of the water in said compartments, caused by convection currents, 25 whereby it will take less time to heat the water and maintain the sides of the arch, which are in the direct path of the convection heat waves, at a temperature of slight variation, thus preserving the life of the 30 material from which the arch is formed as well as assuring rapid circulation and heating of the water.

Other objects will appear hereinafter.

The invention consists in the combination 35 and arrangements of parts hereinafter described and claimed.

The invention will be best understood by reference to the accompanying drawings forming a part of this specification, and in 40 which,

Fig. 1, is a longitudinal vertical sectional detail view of a boiler embodying the invention,

Fig. 2, is a cross sectional detail view of 45 the same substantially on line 2—2 of Fig. 1.

In attaining the objects of the invention, the preferred form of construction, as illustrated in the drawings, comprises a boiler A having the usual fire box 10, combustion 50 chamber 11 and crown sheet 12. The side walls and rear wall of the boiler are surrounded by water compartments 13, 14 and 15 in open communication with the main water compartment 16, as shown. This construction so far described does not consti-

tute any part of the invention, but is merely mentioned to more fully illustrate the same.

The crown sheet herein referred to and indicated by the reference character 12 is supported by a brick arch wall 17 which is 60 in turn supported by my improved arch support 18, said arch support 18 being preferably in the form of a box-shaped structure rectangular in cross section and formed from a continuous sheet of material.

When the arch support 18 is formed of a continuous sheet of material and bent substantially rectangular in shape the joining ends, indicated at 19, are secured together by welding or otherwise and the walls of 70 the arch support are reinforced by transverse rivets or stay-bolts 20 equally spaced apart, as shown in Fig. 2. The arch support 18 is mounted in the combustion chamber of the boiler an applicable distance above 75 the grates 21 thereof and the ends 22 project a trifle into the water compartments 13 and 14, as shown in Fig. 2, said ends being secured by welding or otherwise to the inner walls 23 of the said water compartments. 80

While the drawings illustrate that my improved arch supports the arch wall 17, this need not be so in every case. Where the arch support is merely employed to connect the opposite side water compartments of the 85 boiler together at a location over the fire box the construction or rather formation of the arch support will not be so apt to warp or sag as would a cylindrical arch support, said warping or sagging being caused by the intense heat which the support is subject to.

It will be seen by inspecting the drawings and referring to the description so far set forth that the arch support being in communication with the water compartments 13 and 14, water will be constantly passing through the arch support and inasmuch as the support is directly over the fire box the water passing through the same will be more readily heated than the water in the water compartments 13, 14 and 15 and under such conditions the convection currents will create a rapid circulation therethrough. My object is to increase this circulation and to direct the flow of the circulating water 95 toward the opposite sides of the boiler in order that the water in the compartments 13 and 14 will be equally heated. In attaining this object I mount within the arch support 18 oppositely disposed horizontal trans-

verse baffle-plates 24 and 25 having their adjacent ends 26 in spaced relation with respect to each other and curved downwardly so as to embrace the adjacent rivet or bolt 20. In mounting the baffle-plates 24 and 25 within the arch support 20 the said plates are supported by the transverse rivets 20 which are positioned midway between the top and bottom walls of the arch support.

10 It will be readily understood that when the water in the lower portion of the arch support is heated the heated water will rise to the top to make room for the cooler water and during this convection the currents will 15 be caused to take a course indicated by arrows in Fig. 2, this being accomplished through the medium of the baffle-plates 24 and 25. If at any time it is desired to clean the interior of the arch support or remove 20 the baffle-plates 24 and 25, I provide ports or arm-holes 27 in the outer walls of the water compartments 13 and 14, each arm-hole being provided with screw-threaded plugs 28, which can be readily removed at 25 the desired time.

Some of the advantages of the provision of the baffle-plates, as disclosed herein, have already been mentioned but to realize the importance and value of the baffle-plates the 30 results accomplished must be fully taken into consideration and the chief results accomplished are, viz., the rapid heating of the water, the increased circulation of the convection currents which equally distributes the heated water through the various water compartments and the amount of fuel saved owing to the rapid circulation of the convection currents.

While I have illustrated and described the 40 preferred form of construction for carrying my invention into effect, this is capable of variation and modification without departure from the spirit of the invention. I, therefore, do not wish to be limited to the 45 precise details of construction set forth, but desire to avail myself of such variations and modifications as come within the scope of the appended claims.

Having described my invention, what I 50 claim as new and desire to secure by Letters Patent is:

1. The combination, with the arch wall and the water compartment of a boiler, of a hollow arch support in open communication with said water compartment; means for re-inforcing the walls of said arch support; longitudinally extending bevelled plates removably mounted on said means in said arch support intermediate the bottom

and top thereof and having their adjacent 60 ends in spaced relation with respect to each other, said plates being adapted to direct convecting currents through said arch support; and means permitting withdrawal of the bevelled plates from within said arch 65 support.

2. In a boiler, the combination with the arch wall and the water compartment thereof, of an arch support formed from a single sheet of material and formed rectangular in shape, said arch support being in communication with the water compartments of said boiler, the walls of said arch support being reinforced by transverse stay-bolts; and oppositely disposed plate members carried by said stay-bolts and having their adjacent ends in spaced relation with respect to each other, said plates adapted to direct convecting currents through said arch support.

3. In a boiler, the combination with the arch wall thereof, of an arch support formed from a single sheet of material and formed rectangular in shape, said arch support being in communication with the water compartments of said boiler, the walls of said arch support being reinforced by transverse stay-bolts; and oppositely disposed baffle-plates transversing said arch supports and supported by said stay-bolts, the adjacent 90 ends of said plates being in spaced relation with respect to each other and curved downwardly to embrace the adjacent stay-bolts, said space being adapted to direct the circulation of water through said arch support.

4. In a boiler, the combination with the arch wall thereof, of an arch support comprising a hollow box-shaped structure in communication with the water compartments of the boiler, the side walls of said 100 arch support being reinforced by transverse stay-bolts; oppositely disposed horizontal baffle-plates arranged in said arch support and supported by said stay-bolts and having their adjacent ends curved downwardly to 105 embrace the adjacent stay-bolts, said plates being supported by said stay-bolts in said arch support midway between the top and bottom walls thereof and adapted to direct convecting currents therethrough.

In testimony whereof I have signed my name to this specification in the presence of two subscribing witnesses.

JAMES A. ROSS.
